US0D1016088S

(12) **United States Design Patent** (10) Patent No.: **US D1,016,088 S**
(45) Date of Patent: ** Feb. 27, 2024

(54) **DISPLAY PANEL WITH GRAPHICAL USER INTERFACE**

(71) Applicant: **Hyperconnect LLC**, Seoul (KR)

(72) Inventor: **Seong Yeol Moon**, Seoul (KR)

(**) Term: **15 Years**

(21) Appl. No.: **35/515,179**

(22) Filed: **Jun. 8, 2022**

(80) **Hague Agreement Data**

Int. Filing Date: **Jun. 8, 2022**

Int. Reg. No.: **DM/223341**

Int. Reg. Date: **Jun. 8, 2022**

Int. Reg. Pub. Date: **Sep. 23, 2022**

(30) **Foreign Application Priority Data**

Dec. 10, 2021 (KR) 30-2021-0059778

(51) **LOC (14) Cl.** **14-04**

(52) **U.S. Cl.**

USPC **D14/485**

(58) **Field of Classification Search**

USPC D14/485-488

Primary Examiner — Rachel A. Voorhies

(57) **CLAIM**

The ornamental design for a display panel with graphical user interface, as shown and described.

DESCRIPTION

1. Display panel with graphical user interface

1.1 : Front

The broken lines showing the outer boundaries of the display panel and the remaining broken lines of the graphical user interface in the FIGURE form no part of the claimed design; reproduction 1.1 is a front view of the display panel with graphical user interface.

1 Claim, 1 Drawing Sheet
